UNITED STATES PATENT OFFICE.

NICHOLAS A. COSSENAS, OF NEW YORK, N. Y., ASSIGNOR TO THE ARTHUR CHEMICAL COMPANY, OF NEW HAVEN, CONNECTICUT, A CORPORATION OF CONNECTICUT.

DESIGN FOR A SEAL OR LABEL BLANK OR SIMILAR ARTICLE.

47,662.

Specification for Design.

Patented Aug. 3, 1915.

Application filed April 2, 1915. Serial No. 18,835. Term of patent 7 years.

To all whom it may concern:

Be it known that I, NICHOLAS A. COSSENAS, a citizen of the United States, residing at New York city, in the county and State of New York, have invented a new, original, and ornamental Design for a Seal or Label Blank or similar Article, of which the following is a specification, reference being had to the accompanying drawings, forming a part thereof, and showing in front ele-

vation a seal or label blank embodying my design.

I claim:

The ornamental design for a seal or label blank or similar article, substantially as shown.

NICHOLAS A. COSSENAS.

Witnesses:

C. E. VAUGHN,

AUSTEN DAILEY.
